assignor to Ecodyne Corporation

Filed Sept. 30, 1971, Ser. No. 185,466

Term of patent 14 years

Int. Cl. D23—01

U.S. Cl. D23—3

The figure is a front perspective view of a solution feeder showing my new design, the rear being the same as the front shown except for the connection of the control box support bracket and the two tubes to the tank portion thereof.

I claim:

The ornamental design for a solution feeder, as shown and described.
